JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

TRANSFERRING MECHANISM FOR METAL RODS OR BARS.

1,359,163.

Specification of Letters Patent. Patented Nov. 16, 1920.

Application filed November 2, 1915. Serial No. 59,319.

To all whom it may concern:

Be it known that I, JEROME R. GEORGE, a citizen of the United States, residing at Worcester, in the county of Worcester and Commonwealth of Massachusetts, have invented a new and useful Improvement in Transferring Mechanism for Metal Rods or Bars, of which the following, together with the accompanying drawings, is a specification.

The present invention relates to a transferring mechanism for metal rods or bars and is adapted particularly for the broadside transfer of rods or bars which are advanced in multiple from the cooling bed of a rolling mill. The mechanism, in the present instance, is shown in coöperation with a central feed table or run-out, upon which successive groups of rods or bars are advanced in multiple from a cooling bed; the invention contemplates the broadside transfer of such groups, selectively, to parallel feed tables or run-outs on either side of said central run-out for further operations, such as reshearing, thereon; the transfer to either of said feed tables being accomplished in such a manner that the progress of a group of bars already present on either one of said side feed tables, or the immediate advancement of a fresh group of bars on the central feed table is not interfered with or delayed.

Other objects and advantages of the invention will appear from the following description, taken in connection with the accompanying drawings, in which—

Figure 1 is a view in end elevation of a transferring mechanism embodying my invention.

Fig. 2 is a fragmentary view of the mechanism, looking in the direction of the arrow, on the line 2—2, Fig. 1.

Fig. 3 is an enlarged fragmentary view of the eccentric mechanism for operating the broadside transfer devices.

Fig. 4 is an enlarged fragmentary view in side elevation of said eccentric mechanism.

Fig. 5 is an enlarged perspective view of the supporting means for the ends of the broadside transferring members.

Figs. 6-11 inclusive are diagrammatic representations showing the successive positions of the broadside transferring members in the operation of the invention.

Similar reference characters refer to similar parts in the different figures.

In the drawings I have shown a series of conveyer rolls 1, 1, suitably supported on a framework 2, and constituting a run-out or feed table, for advancing a plurality of bars or rods in multiple, in the direction indicated by arrow A, from a cooling bed, not shown. The conveyer rolls 1 are driven in any well known manner, as by a shaft 4, Fig. 1, connected by gearings 5, 5 with each of said rolls, and may be thrown into and out of operation, as desired, by suitable clutching mechanism, not shown. On either side of the rolls 1, spaced a suitable distance therefrom, are parallel series of conveyer rolls, 6, 6, which appear only as a single roll on each side of Fig. 1. Each series constitutes a feed table for advancing the bars or rods received thereon from the central run-out. Each set of rolls 6, 6 constituting such a feed table is suitably supported on a framework 7 and the rolls are driven in any well known manner, as by parallel shafts 8, connected by gearing 9 with each of said rolls. Rods or bars, assembled in multiple in any well known manner upon the cooling bed, are carried forward in groups successively by the rolls 1 of the central feed table, and may, if desired, be moved against a fixed stop 10, Fig. 2, the bars being accumulated in multiple arrangement nose to nose upon the rolls 1, with their forward ends abutting the stop 10. The mechanism used for transferring each successive group of bars from the rolls 1 of the central feed table to the rolls 6 of either side feed table will now be described in detail, and since the two sets of mechanism are identical, a description of one will suffice for both.

Each transfer mechanism is constituted by a plurality of pairs of bar supporting members 11, 12 extending across the space between the rolls 1 and one set of rolls 6, and arranged in alternating relation to the rolls 1, 1 of the central run-out, as shown in Fig. 2, with the inner ends of said members substantially coextensive with the opposite edges of the rolls 1, as shown in Fig. 1. The outer ends of each pair of members 11, 12 are supported on pairs of rollers 13, 13, journaled on a pin 14 which is supported between the spaced ears of a rocker arm 15 carried by a shaft 16 disposed on the far side of rolls 6, 6. As

shown in Figs. 1 and 2, the pairs of members 11, 12 of the two transfer mechanisms are staggered with respect to each other, so that they extend in one direction, on one side of each roll 1, and in the opposite direction on the other side. The shaft 16 extends approximately the full length of the side feed table, and carries a plurality of these forked rocker arms 15, corresponding in number and position to the pairs of members 11, 12, the ears thereof serving to prevent lateral displacement of the ends of the members, and to maintain them on their respective rollers 13. The shaft 16 is journaled in brackets 17 carried adjacent each roll 6, and is oscillated at intervals through a predetermined arc, by means of a link 18 pivotally attached to an arm 19 on the shaft and connected to a crank disk 20, on a suitably driven shaft 21. By a suitable clutching mechanism, not shown, the shaft 21 can be rotated in either direction, to bring the shaft 16 into the position desired; in one extreme position of said shaft, as shown at the left hand end of Fig. 1, the upper surfaces of members 11, 12 are disposed above the supporting surfaces of the rolls 6; in the other extreme position, which is the normal operating position of the members 11, 12, with respect to the rolls 6, as shown at the right hand end of Fig. 1, in connection with the other side of the feed table, the upper surfaces of members 11, 12 are disposed below the supporting surfaces of the rolls 6.

A shaft 22, supported in brackets 23 carried by the framework 2, extends longitudinally of the central run-out on the same side thereof as the corresponding sets of conveyor members 11, 12. Secured to this shaft are a series of alined rocker arms 24 which provide alined journals for a shaft 25 parallel to the shaft 22, and extending the full length of the central run-out. At intervals on shaft 25, corresponding to the disposition of the pairs of members 11, 12, are provided pairs of eccentrics 26, 27, one for each member, one eccentric of each pair being disposed 180 degrees in advance of the other. The straps of said eccentrics have extensions 30 bolted or otherwise secured to the respective member 11 or 12, as shown at 31, Fig. 3. The shaft 25 has secured thereto a gear 32, in mesh with an idler gear 33 loosely journaled on shaft 22. The latter gear meshes with a gear 34, which is driven by a pinion 35 on the shaft of a gear 36, which is in turn driven by a pinion 37 on the shaft of a motor or other prime mover 38. As shown, the mechanism above described is provided in connection with each set of members 11, 12 on opposite sides of the central run-out. In this manner the power of the motor is transmitted to the corresponding pairs of

members 11, 12, causing the inner end of each member to describe a true circle, of a radius depending upon the eccentricity of its connection with shaft 25. This result follows from the free movement of the outer end of each member back and forth on its roller 13, as heretofore described; it will be clear, moreover, that the angular arrangement of the driving eccentrics for each pair of members on the shaft 25 results in a relative "shuffling" movement in which they describe identical paths, one in advance of the other; in other words, all the members 11 travel together in the same path, while all the members 12 travel together in similar paths 180° behind members 11.

Each shaft 22 carries an arm 39, pivotally connected to a link 40 which is actuated by an eccentric 41 on a shaft 42. The two shafts 42 are independently rotatable, by suitable clutching mechanism, not shown, to rock the shafts 22 independently at selected times, carrying the eccentric shafts 25 into an upper and a lower position as shown in Fig. 1; in one extreme position, as shown on the left hand side of the central run-out, the inner ends of the members 11, 12, are disposed below the supporting surfaces of the rolls 1, while in the other extreme position as shown on the right hand side of Fig. 2, the inner ends of the members 11, 12 are disposed above the supporting surfaces of the rolls 1.

The operation of the mechanism thus far described will now be set forth in connection with one side of the transfer mechanism; for example, the members 11 and 12 on the right hand side of the central run-out. Referring only to the operation of this one side, during the advancement of a multiplicity of bars on the rolls 1, as shown at 43, Fig. 6, the shafts 21 and 42 are so disposed that the corresponding ends of members 11, 12, are below the supporting surfaces of rolls 1 and 6 respectively, as shown in Fig. 6. After a group of bars has been run out on the central feed table, the shaft 42 is rendered operative, to shift momentarily the ends of members 11, 12 above the surface of rolls 1, as shown in Fig. 7, and simultaneously with this shifting the operation of motor 38 begins to "shuffle" the members through the medium of the angularly offset eccentrics 26, 27; obviously, assuming that at the start the bars are supported upon the advancing members 11, they will be carried outwardly, and just as the circular path traversed by the bar supporting portion of said members 11 begins its inward movement, the whole group of bars is picked off by the other members 12 which owing to the angular displacement of the eccentrics 26, 27, are at this time just beginning the upward and outward portion of their circular movement. The shaft 42

is immediately returned to its normal position from which it was rocked momentarily as above described, thereby carrying the inner ends of members 11, 12 whose shuffling movement continues, below the surfaces of rolls 1, as shown in Fig. 8, thus permitting the advancement of another set of bars, indicated at 44, Fig. 8, onto the rolls of the central run-out. The action of the motor 38 continuing, as above set forth, the group of bars 43 is gradually conveyed, step by step toward the side run-out rolls 6, being alternately supported first on the members 11 and then on the members 12, and making its traverse in paths approximating a semi-circle, always above the intermediate positions assumed by said members, *i. e.*, when members 11 and 12 lie in the same plane. In the meantime, a new group of bars is advancing on the central run-out rolls 1, as shown at 44, Figs. 9 and 10. As shown in Fig. 9, the group of bars 43 finally reaches, by the continued shuffling movement of the members 11 and 12 the vicinity of the rolls 6, where the broadside movement is halted by a stop 45; the next step in the movement of the bars will carry them over the rolls 6, and at this point, the shaft 21 is thrown into operation, rocking the shaft 16 and lifting the ends of members 11 and 12 clear of said rolls, as shown in Fig. 10. The members are thereafter returned to normal position by the reverse rotation of shaft 21, allowing the bars 43 to be received upon the rolls 6, and run out, by said rolls, in multiple, for a reshearing operation, or otherwise disposed of, in any usual manner. As soon as the following group of bars 44 is sufficiently advanced on the central run-out, the members 11 and 12 are again momentarily lifted at their inner ends by rotation of the shaft 42 to pick the bars off of the run-out and start their broadside travel, in the manner above described.

In the use of two transferring mechanisms, and two side run-outs, as shown in Fig. 1, the action of each individual side of the apparatus is the same, as above described. The clutching devices for operating the shafts 21 and 42 may be selectively operated at the proper times, so that one group of bars is transferred broadside by the left hand conveyer members 11 and 12, while the next group advanced on the central run-out is transferred broadside by the right hand mechanism, and so forth, alternately. In this way the capacity of the apparatus is greatly increased, enabling it to take care of increased production by the mill.

It will be clearly understood, moreover, that owing to the normal disposition of the ends of members 11, 12 below the supporting surfaces of the rolls 1 and 6 respectively during the operation of said members, the

advancement of successive groups of bars or rods on the central run-out, and the progress of other groups previously deposited on the side run-outs is not interfered with or delayed. Only when it is desired to pick 70 a group of bars off the central run-out, are the inner ends of the members 11 and 12 raised above the rolls 1, and then only momentarily, so as not to interfere with the advancement of the next group of bars on 75 said rolls. Similarly, only when a group of bars is about to be delivered onto one of the side run-outs, are the corresponding outer ends of the members 11, 12, raised above the rolls 6, and then they are lowered in order 80 to effect the deposit of the group of bars on said rolls.

It will be noted that the bar or rod supporting surfaces of the members 11, 12 are made smooth, and for this reason, the supporting surfaces of each set of rolls 6 are disposed slightly lower than the supporting surfaces of rolls 1, so that there will be no tendency for round rods to roll back to the central run-out when being transferred 90 broadside by said members. In other words, in normal positions, the members 11, 12 always slope downwardly from the central run-out in each direction and even when the outer ends of said members are momentarily 95 raised, and the inner ends lowered, as shown at the left hand side of Fig. 1, the members are substantially level; in any case, the inner ends thereof are never lower than the outer ends.

It will be clear that the provision of independent operating devices for raising and lowering the extreme ends of the members 11, 12 on each side of the central run-out gives the operator the widest possible range 105 of selection in controlling the broadside transfer of rods or bars from the central run-out to the side feed tables. A group of bars may be transferred to either table desired, and the following groups may be 110 transferred to the same or the other table wholly at the will of the operator. Moreover, if rendered expedient by a breakdown, or congestion of bars on one of the side feed tables, a group of bars being transferred 115 thereto by the corresponding transfer mechanism may be reversed in direction, by merely reversing the corresponding motor 38, and may be carried past the central run-out onto the other feed table, as will be readily apparent.

I claim.

1. In an apparatus of the character described, a series of rotating rolls for supporting the rolled metal, a stop for limiting 125 the endwise movement on said rolls, a series of bars arranged in pairs on opposite sides of said rolls, with the bars on one side of said rolls overlapping the bars on the opposite side of the rolls, means for imparting a 130

- shuffling movement to the bars of each pair to effect a broadside movement of the rolled metal in either direction, and means for independently raising the receiving ends of said bars on each side of the rolls to lift the rolled metal from said rolls.
2. In an apparatus of the character described, a series of rotating rolls for supporting the rolled metal, a stop for limiting the endwise movement on said rolls, a series of bars arranged in pairs on opposite sides of said rolls, with the ends of said bars overlapping said rolls, means for raising the overlapping ends of said bars to lift the rolled metal from said rolls, upon either side of said rolls at will, and means to impart a shuffling movement to the bars of each pair upon either side of said rolls at will.
- 10 3. In an apparatus of the character described, a series of rotating rolls for supporting the rolled metal, a stop to limit the endwise movement of the metal on said rolls, a series of bars arranged in pairs on opposite sides of said rolls, said bars on one side of said rolls overlapping said rolls and the bars on the opposite side of said rolls, means for raising the overlapping ends of said bars to lift the rolled metal from said rolls upon either side of the rolls at will, and independent means for imparting a shuffling movement to the bars of each pair to effect a broadside movement of the rolled metal over said bars.
- 20 4. In an apparatus of the class described, a support for the rolled metal, a series of bars arranged in pairs on opposite sides of said support, with the ends of said bars on opposite sides of the support overlapping each other, means for raising the overlapping ends of said bars at will, and means for imparting a shuffling movement to the bars of each pair to impart a broadside movement to the rolled metal independently of said raising movement.
- 30 5. In an apparatus of the character described, a series of conveying bars arranged in pairs, means for imparting a circular motion to said bars near one end, a support for the opposite ends of the bars to permit a sliding movement of the bars thereon, a support for the metal to be operated upon overlapping one end of said bars, and a support for the metal overlapping the opposite ends of said bars, and means for raising and lowering the ends of said bars at will above and below said supports.
- 40 6. In an apparatus of the character described, means for supporting the metal to be operated upon, a series of conveying bars overlapping said support, a support for the metal overlapping the opposite ends of said bars, means for imparting a shuffling movement to said bars to effect the transfer of the metal thereon from one end to the other, means for imparting an independent vertical movement to the ends of said bars to raise and lower them above and below said supports to transfer the metal from one support to the bars and to transfer the metal from the bars to the other support.
- 50 7. In an apparatus of the character described, a series of bars arranged in pairs, means for imparting a shuffling movement to the bars of each pair alternately to effect the transfer of the metal from one end of the bars to the other by a broadside movement, a support at the receiving end of the bars for the metal to be operated upon, means for imparting a vertical movement to the receiving ends of said bars at will to lift the metal from its support, a second support at the opposite ends of said bars, and means for imparting a vertical movement at will to the delivery ends of said bars to deliver the metal upon said second support.
- 60 8. In an apparatus of the character described, a series of bars arranged in pairs, means for imparting a shuffling movement to said bars to effect the transfer of metal from one end of the bars to the other by a broadside movement, a support at the receiving end of the bars for the metal to be operated upon, means for imparting a movement in a vertical plane to the receiving end of the bars, to transfer the metal from said support to said bars, a second support for the metal at the opposite ends of said bars, a stop to impede the broadside movement of the metal, and means for moving the delivery ends of the bars in a vertical plane to carry the metal over said stop and said second support, and depositing the metal on said second support.
- 70 9. In an apparatus of the character described, a series of bars arranged in pairs, means for imparting a shuffling movement to said bars to effect the transfer of metal from one end of said bars to the other by a broadside movement, a series of rotating rolls overlapping the receiving ends of the bars, a stop to limit the endwise movement of the metal on said rolls, whereby the pieces of metal are arranged in groups, a second series of rotating rolls overlapping the delivery ends of said bars, a stop between each series of rolls to impede the broadside movement of the metal over said bars and to compact the groups, means for moving the opposite ends of said bars at will in a vertical plane to transfer the metal from one series of rolls to the bars and from the bars to the second series of rolls.
- 80 10. In an apparatus of the character described, a series of rotating rolls, a stop to limit the endwise movement of metal on said rolls, a series of bars arranged in pairs on opposite sides of said rolls, with the ends of said bars overlapping the rolls, a shaft journaled on each side of said rolls and at right

angles to the axes of the rolls, motors operable at will for rotating each of said shafts independently of the other, a second shaft on each side of said rolls parallel with said 5 first shaft, gears connecting said shafts, and a series of eccentrics on said second shaft attached to the bars of each pair, whereby a shuffling movement is imparted to said bars to effect a broadside movement of metal 10 lengthwise said bars.

11. In an apparatus of the class described, a series of rotating rolls forming a central run-out, a stop to limit the endwise movement of metal on said rolls, a series of bars

arranged in pairs on opposite sides of said 15 rolls, means for imparting a shuffling movement to said bars, means for imparting a vertical movement to the receiving ends of said bars, upon each side of said rolls, means for imparting a vertical movement to the 20 delivery end of said bars, with all the actuating means for said bars operable at will and independently of each other.

Dated this 22nd day of October, 1915.
JEROME R. GEORGE.
